UNITED STATES PATENT OFFICE.

FRANK W. TUCKER, OF WINTHROP, ASSIGNOR TO FERDINAND F. FRENCH,
OF WINCHESTER, MASSACHUSETTS.

DESIGN FOR A MONEY-CART.

SPECIFICATION forming part of Design No. 21,246, dated December 15, 1891.

Application filed August 3, 1891. Serial No. 401,618. Term of patent 3½ years.

To all whom it may concern:

Be it known that I, FRANK W. TUCKER, a citizen of the United States, residing at Winthrop, in the county of Suffolk and State of Massachusetts, have invented and produced a new and original Design for Carts, of which the following is a specification, reference being had to the accompanying drawing, forming part hereof.

10 My design is for carts or wagons; and the leading features of my design consist in a horizontal floor *a*, the axle being under the central portion thereof, an extension *b* of said floor at the forward portion thereof, substantially in a straight line therewith, the forward edge of said extension being of concave form, a dasher *c* at the front end of said extension *b* and projecting upwardly therefrom substantially at right angles therewith, the said dasher 15 having a concavo-convex form, and the shafts *d d*, affixed to the upper part of the dasher, one at each side thereof, and projecting forward therefrom at substantially right angles

thereto, the whole forming a graceful and pleasing design for carts. 25

A cart built after this design is of neat and trim appearance, the fact of the dasher being at right angles to the floor and the shafts at right angles to the dasher contributing to this appearance of neatness and trimness. 30

I claim—

The design for carts herein shown and described, the same comprising the horizontal floor *a*, the extension *b*, in a line with the floor *a* and having a concave forward edge, the 35 vertical dasher *c*, affixed to the extension *b* and projecting upwardly from the forward edge thereof, and the shafts *d d*, projecting from the upper part of the dasher, substantially at right angles to the same, as set forth. 40

Boston, August 1, 1891.

FRANK W. TUCKER.
